DEVICE FOR DESTROYING INSECTS

Herbert F. Tomasek, Pittsburgh, Pa., assignor to Pittsburgh Coke & Chemical Company, Pittsburgh, Pa., a corporation of Pennsylvania

Application April 19, 1955, Serial No. 35,585

Term of patent 14 years

(Cl. D31—3)

FIG. 3.

FIG. 1.

FIG. 2.

FIG. 4.

FIG. 5.

Figure 1 is a perspective view of a device for destroying insects showing my new design;

Figure 2 is a top plan view thereof;

Figure 3 is a side elevational view with the pylon in retracted position but without the cover member;

Figure 4 is a top plan view with the cover member mounted thereon; and

Figure 5 is a side elevation view similar to Figure 3 with the cover member mounted thereon.

I claim:

The ornamental design for a device for destroying insects, substantially as shown.
